A. LONGORIA

ELECTRICAL HEATING DEVICE

Filed March 27, 1922

UNITED STATES PATENT OFFICE.

ANTONIO LONGORIA, OF CLEVELAND, OHIO, ASSIGNOR TO THE W. B. McALLISTER COMPANY, OF CLEVELAND, OHIO, A CORPORATION OF OHIO.

ELECTRICAL HEATING DEVICE.

Application filed March 27, 1922. Serial No. 547,022.

To all whom it may concern:

Be it known that I, ANTONIO LONGORIA, a citizen of the United States, and a resident of Cleveland, county of Cuyahoga, and State of Ohio, have invented a new and useful Improvement in Electrical Heating Devices, of which the following is a specification, the principle of the invention being herein explained and the best mode in which I have contemplated applying that principle, so as to distinguish it from other inventions.

The present improvements relating as indicated to electrical heating devices, are more particularly directed to a new and improved electrical stove. One of the principal objects of the invention is the provision of a simple and inexpensive device of this type which may be constructed with a few simple parts and may then be readily assembled into the finished device. Further objects of the invention are improved means for mounting the heating element and for protecting and coiling the frame-work of the device. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a plan view of my improved stove, part of the same being shown in section; Fig. 2 is a vertical section on the line 2—2, Fig. 1; Figs. 3 and 4 are other vertical sections on the lines 3—3 and 4—4, respectively, in Fig. 1; Fig. 5 is a sectional view through a portion of one of the connecting wires; and Fig. 6 is a section showing a modified type of locking means between the frame members.

My improved stove consists of a framework formed in two parts, 1 and 2, the part 1 being provided with an open central portion crossed by a series of transverse ribs 3, and longitudinal ribs 4 which form an open grid-iron for supporting the articles or receptacles to be heated. This frame member 1 is also provided with legs 5 at the corners,

which are integral with this frame member, this entire part being conveniently formed out of a single stamping.

The bottom member 2 is provided with an upturned flange 6 extending around all sides of the bottom and fitting snugly and resiliently into the side walls or side flanges 7 of the main frame member 1. The bottom member is held in position by means of lugs 8 which are formed integrally with the upper frame member 1, and are turned inwardly to engage against and beneath a lower frame member 2 when the latter has been assembled within the upper member.

The heating element consists of a resilient coil 10 which is mounted upon a sheet of insulating and refractory material formed to fit snugly within the upper frame member 1, and to engage against an inwardly extending flange 12 therein. This flange is so formed and the coil 10 is so mounted on the plate 11, that the coils are brought a suitable distance below the openings between the ribs 3 and 4 in the upper frame member to give the best heating effect on any receptacle placed upon the stove without impairing the electrical insulation.

The heating coil 10 is connected at one end to a contact or terminal in the form of a screw 13 and washer 14, the coil being held between the washer and the sheet 11 of refractory material. The other end of the coil is similarly fastened beneath a second screw 13' and washer 14', and the coil is then carried back and forth across a plate 11 and secured at the points where it is bent along the sides of this plate in hooks 15, which are provided with downwardly extending angle portions 16, which fit into slots 17 in the sheet 11. These hooks are adapted to be engaged in the sheets by having the lower portion 18 passed through the slot after which the hook is turned to bring it into position shown in Fig. 4, and the coil 10 is then engaged over and in the hook portion 15. When so engaged, the coil is slightly stretched and the tension in this coil is sufficient to maintain the hook from any accidental engagement from the slot 17 while permitting convenient removal of the hook and coil when necessary for repairs or replacement.

From the two screws 13 and 13', wires are

led through refractory and insulating bushings 19 and 20 which are provided with transverse slots adapted to slip over the edges of the plate 2 in lateral recesses or slots 22 which are formed at either end of this plate. Only one of these two slots is used for these insulating bushings 19 and 20 but the slots are formed in either end to facilitate the handling of the parts in assembling the device as this makes it unnecessary for the operator to pick up the bottom plate in any one position. Connecting wires 23 lead from the terminals 13 and 13' through the bushings 19 and 20 and to a plug (not shown), for attachment to the usual electrical socket.

In Fig. 5 I have shown one of the connecting wires 23 which has been stripped free of its insulating covering at the point where it is held by the terminal post 13 up to and through its passage through the refractory insulated bushing 20. An extremely high heating is maintained in the resistance coil 10 and this heat of course passes along the connections 23 and is high enough to melt certain of the ingredients in the insulated covering on the connecting wire up to the point where these connecting wires to pass outside of the space between the lower plate 2 and the refractory plate 11. It is for this reason that the insulating covering is removed and asbestos or other refractory yarn is wound about the bare wire and then cemented into place by a suitable refractory cement, such for example, as sodium silicate. This coating will not melt or burn under the high temperature of this portion of the wire and also serves to fix the wires in the bushings 20 and prevent their being pulled through the bushings, and in this way, pulled through the terminals. The bushings themselves are formed of lava and are capable of withstanding very much higher temperatures than that maintained in the space between 2 and 11.

It will be noted that the corners 24 of the lower plate 2 are cut out and this provides a passage-way upward along the inner sides of the four legs 5 and to the lower portion of the refractory plate 11. Air is allowed to pass up through these corner openings into the space between the lower plate 2 and the asbestos plate 11, and is then carried through the plate 11 by means of a series of openings 25 along the two sides of this plate. After passing through the holes 25 this air is heated by the coil 10, and then passes upwardly through the grid-iron and into contact with the receptacle or article which is placed thereon. By causing the air which is heated, to be drawn upwardly along and against the inner sides of the four legs of the frame, these legs are cooled very considerably and in this way the outer

frame-work of the stove is cooled to facilitate handling and to prevent overheating of the metal.

In Fig. 6 I have shown a modified means for attaching together the upper frame member 1 and the lower plate 2. In this form the upper member 1 is provided with the same depending flanges as in the previous form but these flanges are now provided with slots 30 while lugs 31 are stamped out from the upwardly extending flanges 6 on the plate 2, these lugs 31 then being bent to pass through the slots 30 and up along the upper sides of the flanges 7.

The simplicity and convenience of assembling my improved stove will be apparent from the foregoing description. The frame-work may be formed from two stampings while the heating unit may be assembled outside of the stove on the refractory plate 11. In assembling the device, the said plate 11 and the heating element thereon, are pressed into the upper portion 1 of the frame until it rests against the flange 12. The plate 11 is formed of a size adapting it to fit snugly within the sides of the frame 1. The heating element is then secured in this position by pressing into place the bottom of plate 2, the flanges 6 of which engage against the lower side of plate 11. The parts are then secured in this relation by bending over the lugs 8. The device may be equally readily taken apart by merely bending back the lugs 8 and withdrawing first the plate 1 and then the plate 11 with its heating coils. Before inserting the plate 1, the insulating buttons 19 and 20 are slipped into one of the recesses 22 in the ends of this plate which fixes the wires with respect to the stove and prevents the accidental pulling out of the wires from beneath the terminals 13 and 13'.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the character described, the combination of a frame member provided with a perforated supporting surface, a depending flange along the sides of said surface and a plurality of legs depending from such flange, a bottom plate engaging within and between such flanges on said frame member, and a heating element mounted between said frame member and said plate, said bottom plate being provided with openings adjacent each of said legs on said frame member, whereby air may pass upwardly along said legs to said heating element.

2. In a device of the character described, the combination of a frame member provided with a perforated supporting surface, a depending flange along the sides of said surface and a plurality of legs depending from such flange, a refractory insulating plate bearing an electrical heating element on its upper surface, said plate being mounted between such flanges on said frame member, and said plate being provided with a plurality of openings therethrough, a bottom plate provided with flanges fitting within such flanges on said frame member, such bottom plate flanges engaging said refractory plate, and said bottom plate having openings therethrough adjacent said legs on said frame member. 10 15 20 25
3. An electrical heating device comprising a plate provided with spaced slots therein and two terminal posts, an electrical resistance coil having its ends connected to said terminal posts, hooks mounted in such slots in said plate, and said coil being secured at different points along its length to said hooks, said hooks being spaced to require tensioning of said coil when attached thereto. 30
4. An electrical heating device comprising a plate provided with spaced slots therein and two terminal posts, an electrical resistance coil having its ends connected to said terminal posts, hooks removably mounted in such slots in said plate, and said coil being removably secured at different points along its length to said hooks, said hooks being spaced to require tensioning of said coil when attached thereto, and said hooks being formed to disengage from such slots when twisted in a direction opposite to the tensioning action of said coil, whereby said hooks are held against accidental removal while said coil is attached thereto. 40 45 50 55
5. In a device of the character described, the combination of metal frame members fitting one within the other to provide a space therebetween, a heating coil mounted between said members, one of said members being provided with a slot in one side, refractory bushings provided with lateral slots engaging the walls of such slot in said frame member, and connections for said coil passing through said buttons. 60 65 70
6. A unitary frame member for an electrical heating device of the character described, said member being formed of a single piece of sheet metal and comprising a grid-iron supporting plate, flanges depending from the sides thereof and legs extending from said flanges. 75 80 85
7. In a device of the character described, the combination of spaced frame members, an electrical heating coil mounted therebetween, one of said members being provided with an opening therein, a refractory bush- 90 95 100 105 110 115 120 125
- ing mounted in such opening, a wire leading from said heating coil through said bushing, and a refractory coating encasing said wire and extending from its point of attachment to said coil to a point beyond said bushing. 70
8. In a device of the character described, the combination of spaced frame members, an electrical heating coil mounted therebetween, one of said members being provided with an opening therein, a refractory bushing mounted in such opening, a wire leading from said heating coil through said bushing, and a refractory coating encasing said wire and extending from its point of attachment to said coil to a point beyond said bushing, said coating filling the interior of said bushing and fixing said wire against movement therethrough. 75 80 85
9. An electric table stove comprising a one-piece body, a pan having its marginal edges supported by said body, an insulator having its marginal edges supported by the marginal edges of said pan, and a sinuous heating element on said insulator. 90
10. An electric table stove comprising a one-piece body, said one-piece body having a foraminous cooking top with the heating element spaced from and below said cooking top, a pan having its marginal edges supported by said body, an insulator having its marginal edges supported by the marginal edges of said pan, and a sinuous heating element on said insulator. 95
11. An electric table stove comprising a one-piece body, a pan having its marginal edges supported by said body, an insulator having its marginal edges supported by the marginal edges of said pan, a sinuous heating element on said insulator, and said body having side walls and legs with said pan supported by inturned lower edges of the body side walls. 100 105
12. An electric table stove comprising a one-piece body, a pan having its marginal edges supported by said body, an insulator having its marginal edges supported by the marginal edges of said pan, and a sinuous heating element on said insulator, said insulator having binding posts and coil holders for said sinuous heating element, and said pan having an insulator for leading out wires. 110
13. As a new article of manufacture, an electric stove body pressed from sheet metal to form a foraminous cooking top and legs. 120
14. As a new article of manufacture, an electric stove body pressed from sheet metal to form a foraminous cooking top having side walls with legs at the juncture of the side walls. 125
15. As a new article of manufacture, an electric stove body pressed from sheet metal to form a foraminous cooking top having side walls with legs at the juncture of the

4
side walls, and said side walls having in-turned lower edge portions adapted for supporting a heating element in said body.

16. In an electric table stove, a flat insulator, a bared sinuous heating element on said insulator extending from end to end of said insulator, and means at the ends of said insulator holding the ends and intermediate portions of said heating element.

10 17. In an electric table stove, a flat insulator, a bare sinuous heating element on said insulator extending from end to end of said insulator, means at the ends of said insulator holding the ends and intermediate 15 portions of said heating element, and a pan

under said insulator supporting the ends and sides of said insulator with said insulator in spaced relation to said pan.

18. An electric table stove comprising a foraminous cooking top, a bared sinuous heating element below and in spaced relation to said cooking top, an insulator under said heating element and supporting said heating element, and a pan under said insulator in spaced relation thereto, said pan 20 25 supporting said insulator.

Signed by me, this 24th day of March, 1922.

ANTONIO LONGORIA.
